ELECTRIC CUTTER FOR CEILINGS, WALLS,
AND THE LIKE

Ernest Heubach, New York, N. Y.

Application April 25, 1934, Serial No. 722,327

12 Claims. (Cl. 72—128)

This invention relates to new and useful improvements in an electric cutter for cracks in ceilings and walls of plaster, etc.

The invention has for an object the construction of a device as mentioned which is characterized by its ability to absorb dust and small particles produced when cutting out the plaster of a wall.

Still further, the invention proposes the arrangement of a tubular casing open at the front end and having a partition dividing it into front and rear compartments, the arrangement of an electric motor in the closed rear compartment having its shaft coaxially entering into the front of said casing, and a cutting tool arranged upon the front of said shaft for cutting the plaster of a crack.

Furthermore, the invention contemplates the provision of a hollow conduit connecting the front compartment with the inlet of a dust bag collector, and the provision of a suction fan on the shaft drawn through the front of the casing and discharge through said conduit.

Furthermore, as another object of this invention it is proposed to arrange a baffle within the front of the casing to coact with the action of the suction fan in moving air through the conduit.

Still further, it is proposed to provide a thrust bearing for the motor so as to take up the thrust due to operating the cutting tool.

Another one of the objects of this invention is the arrangement of telescopic shaft sections composing the front portion of the shaft for said tool, and a mechanism for telescopically moving said shaft sections to extend or retract the cutting tool relative to the front of the casing.

Furthermore, the mechanism is also proposed for latching the telescoping shafts in various extended positions.

The invention also contemplates an arrangement whereby a grinding tool such as a sand-paper disc may be substituted for the cutting tool.

As another object of this invention it is proposed to construct a device as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a longitudinal sectional view of a device constructed according to this invention.

Fig. 2 is a fragmentary view of the front portion of Fig. 1 but illustrating a different tool substitute.

Fig. 3 is a fragmentary view of a portion of Fig. 1 but illustrating a modification of the invention.

Fig. 4 is a side elevational view of another type of cutting tool for the device.

The electric cutter for cracks in ceilings, walls, etc., comprises a tubular casing consisting of a front casing section 10 detachably connected with a rear casing section 11, said casing being provided with a front open end 12 and also being provided with a partition 13 for dividing it into a front compartment and a closed rear compartment. An electric motor 14 is arranged within the closed rear compartment of the casing and has its shaft 15 extending exactly through the center of the casing. A cutting tool 16 is detachably mounted upon the end of the shaft 15. A hollow conduit 17 connects the front of the casing with the inlet 18 of a dust bag collector 19. A suction fan 20 is arranged upon the shaft 15 for drawing through the front of the casing and discharging through the conduit 17.

The cutting tool 16 is shown of conical shape and comprises a plurality of radial blades, and is formed with a threaded stud 21 at the rear end adapted to engage into a threaded aperture formed in the end of the shaft 15. The cutting tool 16^a in Fig. 4 is similarly constructed but is of substantially hemispherical shape. A spider construction 22 is mounted within the front end of the casing and has openings for the passage of air, and a hub portion 23 equipped with a bearing 24 for the shaft 16. A baffle plate 25 is arranged within the front portion of the casing and acts in conjunction with the suction fan 20 to direct the discharge through the conduit 17. More particularly, the suction fan 20 is of the centrifugal type having a central inlet and discharging in the periphery. The conduit 17 engages into the casing at a peripheral portion of the suction fan. A boss 26 is formed on the side of the casing into which the end of the conduit 17 engages.

The conduit 17 is in the form of a handle by which the device may be supported and manipulated. The rear of the conduit 17 terminates in a portion 28 which is attached upon the rear closed end of the casing section 11. The portion 28 is also provided with a flange 29 which connects with the inlet 18 of the dust bag collector. A suitable arrangement is provided so that the inlet 18 may be separated from the flange 29.

The casing section 11 has a reduced shoulder 30 at the front end upon which the rear end of the casing section 10 engages. Frictional means or other means may be provided for holding these casing sections together. Several bent openings 31 are formed in the casing section 11 to prevent overheating of the motor. A fan 32 is mounted upon the shaft 15 of the motor so as to produce

commotion or circulation within the compartment. The rear end of the motor shaft 33 is mounted within a bar 34 mounted upon a disc 35 used for closing the end of the casing. A thrust bearing is arranged to resist the pressure of the shaft 15 and comprises a bracket 36 attached upon the disc 35 for supporting an expansion spring 37 carrying a bearing ball 38 at its end engaging against the end of the shaft 33.

10 The operation of the device consists in holding the handle, the conduit 17, and moving the device along so that the cutter 16 cuts the material of the plaster in the sides of the crack. The open end 12 of the casing preferably should be in 15 intimate contact with the wall or ceiling so that a large amount of dust is drawn in by the suction fan. This dust is discharged and collected in the dust bag 19.

In Fig. 2 another arrangement of the device 20 has been illustrated in which a sandpaper block 40 is shown substituted for the tool 16. This sandpaper block is also shown provided with a threaded stud 21 which threadedly engages in the end of the shaft 15. The device may thus be used 25 for finishing the plaster surface or other similar purposes.

In Fig. 3 a modified arrangement has been disclosed 30 in which provision is made for slightly extending and slightly retracting the cutting tool. With this arrangement it is possible that first a small cut be taken in the crack of the plaster and then a larger cut and in this manner the front open end of the casing may always be in 35 intimate contact with the surface of the wall.

35 More particularly, the means mentioned in the previous paragraph comprises telescopic shaft sections 15^a and 15^b substituted for the shaft 15. The shaft section 15^b is integral with the rotor of the motor and has a square portion extending 40 into a corresponding opening in the section 15^a to transmit rotations. A flange 41 is fixed upon the shaft section 15^a and an expansion spring 42 acts between the partition or spider 22 and the flange 41 for normally urging the shaft section 45 15^a into a retracted position. A pin 43 extends from the side of the shaft section 15 and works in an elongated slot formed in the end of a lever 44 which is pivotally supported at 45 upon the casing of the device and which extends through 50 an opening to the exterior. A link 46 connects with the extended end of the lever 44 and connects with a trigger 47. This trigger is pivotally mounted intermediately at 48 upon the conduit 17. The front end of the trigger extends into 55 the vicinity where the index finger would be so that it may be readily manipulated.

A rack 49 is pivotally supported at the point 50 upon the spider 22 and is engageable with a tooth 51 projecting from the shaft section 15^a. This rack, in a horizontal position engages the tooth 51 and also abuts against a stop 52 projecting from the casing of the device. A link 53 is 60 equipped with a pin working in a slot in the end of the rack 49 and the link 53 extends to the exterior of the casing. A ring 54 is attached upon the extended end of the link 53. A coaxial spring 55 acts between the casing of the rack 49 to normally urge it into the horizontal position. The link 53 is composed of two sections including an 65 outer section formed with an elongated slot 56 in which a pin 57 from the inner section engages. The arrangement is such that the link 53 may be extended to a point at which the outer section may be pivoted at right angles and moved to a 70 position so as to be locked outside of the casing.

Then the rack 49 is held in an inoperative position.

In operation the rack 49 may be moved to its inoperative position so that the extension and retraction of the cutting tool can be controlled instantly by moving the trigger 47. If desired, the cutting tool may be latched in any of its extended positions by allowing the rack 49 to move to the horizontal position. In other respects the device functions as previously described relative to the preferred form.

5

10

Having thus described my invention, what I claim as new, and desire to secure by United States Letters Patent is:—

1. An electric cutter for cracks in ceilings and walls of plaster, etc., comprising a tubular casing open at the front end and having a partition dividing it into front and rear compartments, an electric motor in the closed rear compartment and having its shaft co-axially extending through the front end of the casing, a cutting tool on the front end of the shaft for cutting the plaster of the crack, a hollow conduit connecting the front compartment with the inlet of a dust bag collector, and a suction fan on said shaft for drawing air through the front of the casing and discharging through said conduit.

15

2. An electric cutter for cracks in ceilings and walls of plaster, etc., comprising a tubular casing open at the front end and having a partition dividing it into front and rear compartments, an electric motor in the closed rear compartment and having its shaft coaxially extending through the front end of the casing, a cutting tool on the front end of the shaft for cutting the plaster of the crack, a hollow conduit connecting the front compartment with the inlet of a dust bag collector, and a suction fan on said shaft for drawing air through the front of the casing and discharging through said conduit, a baffle plate with a central opening being arranged to the front of the suction bag.

30

3. An electric cutter for cracks in ceilings and walls of plaster, etc., comprising a tubular casing open at the front end and having a partition dividing it into front and rear compartments, an electric motor in the closed rear compartment and having its shaft coaxially extending through the front end of the casing, a cutting tool on the front end of the shaft for cutting the plaster of the crack, a hollow conduit connecting the front compartment with the inlet of a dust bag collector, and a suction fan on said shaft for drawing air through the front of the casing and discharging through said conduit, a baffle plate with a central opening being arranged to the front of the suction bag, and said fan being of the centrifugal type discharging through the ends of the conduit arranged on the periphery of the casing in the vicinity of the fan.

35

4. An electric cutter for cracks in ceilings and walls of plaster, etc., comprising a tubular casing open at the front end and having a partition dividing it into front and rear compartments, an electric motor in the closed rear compartment and having its shaft coaxially extending through the front end of the casing, a cutting tool on the front end of the shaft for cutting the plaster of the crack, a hollow conduit connecting the front compartment with the inlet of a dust bag collector, and a suction fan on said shaft for drawing air through the front of the casing and discharging through said conduit, said rear compartment being formed with several vents.
